UNITED STATES PATENT OFFICE.

JOHN P. KIRST, OF TAMPICO, ILLINOIS, ASSIGNOR OF ONE-FOURTH TO CHRISTOPHER C. KIRST, OF TAMPICO, ILLINOIS.

DESIGN FOR A TRUNDLE.

Application filed September 29, 1925. Serial No. 14,951. Term of patent 7 years.

To all whom it may concern:

Be it known that I, JOHN P. KIRST, a citizen of the United States, residing at Tampico, in the county of Whiteside and State of Illinois, have invented a new, original, and ornamental Design for a Trundle, of which the following is a specification, reference being had to the accompanying drawing, forming part thereof.

The figure is a perspective view of the trundle showing my new design.

I claim:

The ornamental design for a trundle, as shown.

JOHN P. KIRST.
